UNITED STATES PATENT OFFICE.

BENJAMIN FRANKLIN MERSSMANN, OF WEBB CITY, MISSOURI.

DESIGN FOR A DISPENSING VESSEL.

SPECIFICATION forming part of Design No. 33,582, dated November 20, 1900.

Application filed October 26, 1900. Serial No. 34,516. Term of patent 14 years.

To all whom it may concern:

Be it known that I, BENJAMIN FRANKLIN MERSSMANN, a citizen of the United States, residing at Webb City, in the county of Jasper 5 and State of Missouri, have produced a new and original Design for a Dispensing Vessel, of which the following is a specification.

This invention relates to a new and original design for a dispensing vessel, the essential 10 feature residing in the design illustrated in the accompanying drawing, which represents a perspective view of a liquor-dispensing vessel disclosing the design.

The numeral 1 designates a support or base 15 in the form of a portion of a barrel or keg with the head end 2 uppermost. On the said head end of the support or base the representation of a complete barrel or keg 3 is permanently disposed in a horizontal plane with 20 the opposite extremities projecting beyond

the marginal confines of the head of the support or base. A bowed projection 4 stands upwardly from the barrel or keg 3, and in the center of the upper portion of the latter is a dome-shaped knob 5 and at one end a downwardly-extending device 6, having an upright member 7. The support or base and the barrel or keg 3 are surrounded with bands 8. 25

Having thus described the invention, what is claimed as new is—

The design for a liquor-dispensing vessel, 30 as herein shown and described.

In testimony that I claim the foregoing as my own I have hereto affixed my signature in the presence of two witnesses.

BENJAMIN FRANKLIN MERSSMANN.
